(57) **CLAIM**

The ornamental design for an axle extension apparatus for axle wheel alignment, as shown and described.

DESCRIPTION

FIG. 1 is a bottom view of an axle extension apparatus for axle wheel alignment showing my new design;

FIG. 2 is a top view thereof;

FIG. 3 is a front view thereof with parts disassembled for ease of disclosure;

FIG. 4 is a side view thereof with parts disassembled for ease of disclosure;

FIG. 5 is a front perspective view thereof; and,

FIG. 6 is a top perspective view thereof.
